(57) **CLAIM**

The ornamental design for a tire, as shown and described.

DESCRIPTION

FIG. 1 is a perspective view of a tire according to my new design;

FIG. 2 is a right side view thereof, the left side view being a mirror image;

FIG. 3 is a front side view thereof; and,

FIG. 4 is a rear view thereof.

The broken line depictions illustrate unclaimed portions of the tire.
